N. Y., a corporation of New York

Application November 21, 1952, Serial No. 22,401

Term of patent 14 years

(Cl. D21—1)

To all whom it may concern:

Be it known that I, Scott R. Bond, a citizen of the United States and a resident of North Plainfield, in the county of Somerset and State of New Jersey, have invented a new, original, and ornamental Design for a Tassel for Pull Cords, of which the following is a specification, reference being had to the accompanying drawing, forming part thereof.

Fig. 1 of the drawing is an elevation of the tassel for pull cords showing my new design.

Fig. 2 is a top view of the same.

I claim:

The ornamental design for a tassel for pull cords, as shown.

SCOTT R. BOND.
